UNITED STATES PATENT OFFICE.

FRANK AHLBURG, OF SAN FRANCISCO, CALIFORNIA, ASSIGNOR TO ELECTRIC FRUIT MARKING CO., OF SAN FRANCISCO, CALIFORNIA, A CORPORATION OF CALIFORNIA.

FRUIT-MARKING MACHINE.

Application filed June 5, 1919. Serial No. 301,859.

To all whom it may concern:

Be it known that I, FRANK AHLBURG, a subject of the German Government, and a resident of the city and county of San Francisco and State of California, have invented a new and useful Fruit-Marking Machine, of which the following is a specification.

My invention relates to machines for marking or branding fruit.

10 An object of the invention is to provide means for branding a trade-mark, trade-name or other design upon the surface of fruit.

15 Another object of the invention is to provide means for marking fruit, in which the marking means or die is composed of a plurality of resiliently mounted die elements, each one adapted to bear against the surface to be marked with the same pressure, 20 so that fruit or other objects having irregularly curved surfaces may readily be marked.

25 Another object of the invention is to provide a marking machine including improved means for heating and mounting the marking dies.

30 The invention possesses other objects and features of advantage, some of which, with the foregoing, will be set forth in the following description of the preferred form 35 of my invention which is illustrated in the drawings accompanying and forming part of the specification. It is to be understood that I do not limit myself to the showing made by the said drawings and description, as I may adopt variations of the preferred form within the scope of my invention as set forth in the claims.

40 Referring to the drawings:

45 Figure 1 is a perspective view of the marking machine, portions being broken away to disclose the structure.

45 Figure 2 is a plan view, portions of the top being broken away.

45 Figure 3 is a perspective view of a modified form of my machine, portions being broken away to disclose the structure.

50 My marking machine comprises an outer casing 2 and an inner casing 3 between which is a heat insulating layer 4. The inner casing is adapted to contain a quantity of mercury 6 and means for heating the mercury is provided by a heating coil 7 arranged in the bottom of the casing and con-

nected by conductors 8 to any suitable source of current.

Arranged on the top of the casing is an inner cover plate 11 having an aperture therein, the plate being formed with a downturned flange 12 surrounding the aperture, thus providing a guideway in which the parallel die frames 13 are slidably arranged. A die element 14 is secured on the upper end of each frame, and there are as many die frames as there are characters or elements in the mark to be applied, and each frame and its die element is separately slidable longitudinally on its own axis within the flange 12, the several axes being parallel. Lateral displacement of each frame is prevented by forming it with grooves 15 on the sides adapted to engage corresponding ridges 16 formed on the adjacent surfaces of the flange 12.

The die frames 13 are shaped in the form of an inverted T, and on each end of the cross bar 17 of the die frame is secured by screws 18, a float 19 comprising a hollow casing formed conveniently of light tubing. Because of the closeness of spacing of the die frames, the cross bars 17 are of different lengths, so that in plan the floats are in staggered relation in two or more rows as seen in Figure 2. As shown in Figure 1 the longer cross bars are arranged a little below the shorter ones to avoid interference of the cross bars with the bottoms of the inner floats. Preferably the outer floats are somewhat larger than the inner ones to provide increased buoyancy for the larger die frames so that each of the dies is pressed upwardly with a like force. A short horizontally extending flange 21 formed by the overhanging edge of the outer cover plate 22, on each side of the dies provides a stop 25 against which the upper ends of the die frames impinge, and the level of the mercury and the proportion of parts is such that the die frames are normally buoyantly retained against the stops with equal pressure.

Means are provided for varying the mercury level in the casing. A closed elliptical drum 23, provided with a nipple 24 on the side adjacent one end, is rotatably arranged 105 on one side of the casing. The nipple has a conically formed end which is pressed to a seat in the casing wall by the plate 25 se-

cured to the casing by screws 26. The axis of the nipple lies approximately in the normal level of mercury, which fills the drum to the same level as in the casing. Rotation of the drum varies the amount of space therein occupied by the mercury, and hence movement of the drum about its axis allows mercury to run therefrom into the casing or from the casing into it according to its position, thus varying the level of mercury in the casing and altering as may be desired the buoyancy of the floats which normally project a small amount above the level of the mercury. By tipping the drum 23 so that its long axis is vertical mercury will flow therefrom to raise the level in the casing to the highest point thus giving the maximum buoyancy to the floats and the strongest upward pressure to the dies.

20 Cork blocks 27 are spaced on each side of the dies 14, their adjacent upper edges being beveled to provide a run-way for guiding the fruit to be marked over the dies.

25 A thermostat bulb 28 of well known type is arranged in the mercury for the automatic control of the current energizing the heating coil.

30 The mercury is heated by the coil 7 and communicates its heat to the immersed die frames which in turn conduct the heat to the dies carried thereon.

35 To use the machine, the fruit is placed side down on the run-way between the cork blocks and rolled firmly over the hot dies, which resiliently give way as the fruit passes over them, leaving an indelibly and evenly branded mark in the skin of the fruit. If desired mechanical feeding means, such as that shown in the copending application 40 Serial Number 223,651 may be incorporated with my present apparatus.

45 In Figure 3 I have shown a modified form of marking machine in which rectangular die frames 31 are arranged to slide within a copper or aluminum block 32, in which a heating coil 33 is embedded. The block 32 is supported on ledges 34 formed on the walls of the casing, and a layer 36 of heat insulating material is interposed between the block 50 and the casing and cover plate.

55 The die frames are each provided with a heavy heat insulating pad 37 on the lower end. Pendently supported from the cover plate 22 by screws 38 is a bar 39 extending across the casing below the die frames. The bar is provided with a number of pins 41, one below and alined with each die frame, and a coil spring 42 extending from the plate up past the end of the pin to the alined pad 37 is disposed about each pin, thus resiliently supporting the die frames upon the bar. By turning the screws 38, the bar may be raised or lowered to vary the tension on the springs. Lateral movement of the plate 60 is prevented by seating the ends of the

screws 38 loosely in sockets formed in the bosses 43 on the bottom of the casing. Each of the die frames is thus resiliently held in its upper position against the overhanging edge of the cover plate, while the springs 70 are protected from excessive heat.

A thermostat bulb 44 is arranged in the block 32 for the automatic control of the temperature of the block. The heat from the block is conducted to the die frames and thence to the dies. The operation of the machine is similar to that already described.

I claim:

1. In a marking machine, a die comprising a plurality of die elements having parallel axes, means for mounting said elements for longitudinal motion on said axes, means for resiliently retaining said elements in predetermined position, stationary means contiguous with said die elements for heating said die, and means for permitting articles to be marked to be rolled over said die. 80

2. In a marking machine, a plurality of parallel frames, a die on each of said frames, means for resiliently supporting said frames, and means for varying the resilience of said supporting means. 90

3. In a marking machine, a movable die, a float connected to said die, and a body of liquid for supporting said die by the buoyancy of said float. 95

4. In a marking machine, a movable die, a float for supporting said die, a body of liquid for buoyantly supporting said float, and means for limiting the upward movement of said die. 100

5. In a marking machine, a body of liquid, and a die buoyantly supported on said liquid. 105

6. In a marking machine, a body of liquid, a die buoyantly supported on said liquid, and means for varying the level of the liquid. 110

7. In a marking machine, a body of liquid, a die buoyantly supported on said liquid, and means for heating the liquid to heat the die. 115

8. In a marking machine, a body of liquid, a die buoyantly supported on said liquid, means for heating the liquid to heat the die, and means for permitting articles to be marked to be rolled over said die. 120

9. In a marking machine, a die comprising a plurality of die elements, a frame for supporting each of said die elements, guide means in which said frames are slidably arranged, floats on said frames, a body of liquid supporting said floats, and means for heating the liquid whereby the dies are heated by conduction through said frames. 125

10. In a marking machine, a casing, a top plate on said casing, a body of mercury in said casing, a plurality of frames buoyantly supported on said mercury and slidably arranged in said top plate, a die element on 130

each of said frames, and means for heating said mercury to heat said dies by conduction through said frames.

11. In a marking machine, a casing, a top plate on said casing, a body of mercury in said casing, a plurality of frames buoyantly supported on said mercury and slidably arranged in said top plate, means for limiting the upward movement of said frames, a die element on each of said frames, means for heating the mercury to heat the dies by con-

duction through said frames, and means for permitting articles to be marked to be rolled across said dies.

In testimony whereof, I have hereunto set ¹⁵ my hand at Waterbury, Conn., this 26th day of May, 1919.

FRANK AHLBURG.

In presence of—

JOHN T. MONZAN,
WALTER E. MONAGAN.
